UNITED STATES PATENT OFFICE.

JACOB S. THORN, OF PHILADELPHIA, PENNSYLVANIA.

DESIGN FOR A SHINGLE OR ROOFING-PLATE.

SPECIFICATION forming part of Design No. 18,210, dated March 27, 1888.

Application filed February 27, 1888. Serial No. 265,518. Term of patent 14 years.

To all whom it may concern:

Be it known that I, JACOB S. THORN, of the city and county of Philadelphia, State of Pennsylvania, have invented and produced a new and original Design for Metallic Roofing-Plates or Shingles, of which the following is a specification, reference being had to the accompanying drawings, which form a part thereof, and in which—

10 Figure 1 is a perspective view of my newly-designed roofing-plate, and Fig. 2 a side view of the same, these two views being deemed necessary to fully illustrate my design.

15 My new design consists of a roofing-plate having a thickened lower edge of what I will call a "semi-octagonal" form, by which I mean that it is bounded by lines which converge downward from the sides toward the center line of the plate and a line at right angles to 20 the said center line intersecting said converging lines, said plate having also an elongated projection extending along the median line on its upper surface.

25 A is the face or upper visible part of the shingle, having preferably side edges, *a a*, parallel to its median line.

B is the semi-octagonal raised or struck-up lower edge of the shingle, bounded by the converging lines *b b* and the intersecting line *b'*.

C is the elongated projection, extending, as 30 shown, along the median line of the shingle.

D indicates the upper portion of the visible face of the shingle, which is generally only clearly outlined when coupled with similar shingles, and therefore forms no part of my design. The dotted lines indicate flanges, edges, &c., of the shingle, which are situated outside of its visible face, and may be of any desired construction without in any way affecting my design. 35

I claim—

The design for a metallic shingle or roofing-plate herein shown and described, the same consisting of a shingle having a thickened lower edge of semi-octagonal form, and the 45 elevated elongated projection extending along the median line of its upper surface.

JACOB S. THORN.
